UNITED STATES PATENT OFFICE

2,429,014

AUTO JACK

Robert C. Christopher, Chicago, Ill.

Application July 22, 1946, Serial No. 685,545

12 Claims. (Cl. 254—93)

1

My invention relates to automobile jacks, preferably of the type which may be used in connection with supporting, or raising a car by engagement of certain portions of my jack invention with the bumper of the automobile, which usually is equipped with front and rear bumpers, thus providing access to the jacking up of the front, or the rear of the automobile.

A prime object of my invention is to provide an automobile jack, which is comprised of a cylinder and piston structure confining a gas expansion compartment, the said jack being distendible or extensible by means of chemical reaction, thus requiring no mechanical means for lifting the car, hence operating on the pneumatic principle.

Another object of my invention is to provide a jack of the afore-mentioned character, which has a limited articulate movement in its attachment to the base of the jack.

A further object of my invention is to provide an adjustable bumper support, which can be adjusted to various raised, or lowered positions.

A further object of my invention is to provide in a jack of the afore-mentioned character, provided with a hollow piston structure having a liquid containing cavity therein, it being further provided with valve means for permitting certain portions of the said liquid to be passed into the gas chamber of the said jack body, the body also being provided with means for placing therein a chemical cartridge which, in its reaction with the liquid supplied, will create gas pressure sufficient to lift and raise the said jack, and/or the load supported thereon.

A further object of my invention is to provide a jack having a dual purpose, one in being capable of raising a load on the one hand, the said load being raised through chemical action as heretofore mentioned; yet when the load is to be lowered the gas under pressure confined within the jack body may be exhausted, or may be connected through suitable connecting means, such as a hose to tires, using the gas pressure confined within the jack for inflation of the said tire.

Another object of my invention is to provide a jack of the afore-mentioned character, which is responsive and reactable through gas pressure generated therein, the said jack means being also useful for inflation purposes of tires when not used for raising a load.

A further object of my invention is to provide an automobile jack of the afore-mentioned character which is practical, and efficient in construction, and operation, which can be used for raising a load, or as an inflation pump, the entire struc-

2

ture being of such simple elemental arrangement as to warrant economical manufacture thereof in quantity production.

Other features, related objects, and ancillary advantages inherent in my invention will become apparent from an examination of the accompanying drawings, wherein like symbols designate like parts, and in which;

Fig. 1 represents a longitudinal cross-sectional view of my invention.

Fig. 2 represents a fragmentary side view of my invention, with a certain portion thereof indicated in cross-section, in order to more clearly depict the structural features thereof.

Fig. 3 represents a view looking in the direction of arrows 3—3 on Fig. 2.

Fig. 4 is a view taken looking in the direction of arrows 4—4 on Fig. 1.

Fig. 5 is a composite view showing how the jack, comprising my invention, may be used in order to act as an inflation pump for a tire.

Fig. 6 is a transverse cross-sectional view taken on the line 6—6 of Fig. 1.

Fig. 7 is a transverse cross-sectional view taken on the line 7—7 of Fig. 5.

Fig. 8 is a view taken, substantially, on the line 8—8 of Fig. 1.

Referring to the various views, my invention is generally designated 9. It consists of a cylinder, or body 10, having a substantially open top, and a closed bottom portion 11. The said bottom portion is secured firmly to a pivoting stud 55 having a headed portion 59 which is slightly rounded, or arcuate, as indicated 60. The said pivoting stud 55 is secured to the base 56 which is provided with an extension 57 having a recess 58, a securing nut 70 holding the body 10 in limited adjustable and pivotal movement. The said jack body 10 has a compartment therein 12, 40 which will be designated as the gas expansion chamber for motivating the piston 14, which is also hollow and has a cavity 19 therein. The piston is provided with piston rings 15 for sealing the operation thereof within the chamber 12, the upper portion of the body or cylinder 10 being provided with a lip 13, the piston being provided with a mating keyway 54, in which the said lip operates, so that on its upward travel, the bottom of the keyway 54 will abut against the lip 13 as a stop, and in the collapsed movement, the recess portion 36 causes the shoulders 62 and 63 to rest on one another, in order to maintain the jack in its collapsed position.

The cavity 19 within the piston is used for filling the same with a suitable liquid, which will

have the proper reaction when admitted into the chamber 12, subsequently to the insertion of a chemically reactive cartridge 46 within the compartment, or cavity 12. The substances that may be used could be sodium for the cartridge 46, and water for the liquid 45. The liquid is admitted into the compartment 12, by means of a valve structure consisting of the valve element 17, of frusto-conical shape, which seats against the frusto-conical valve opening 16, in the bottom 14 of the piston, and which will admit small quantities of the liquid 45 to drop down into the cavity 12 below the bottom 14 of the piston.

The top portion of the piston is reinforced as indicated at 20 and is provided with an inner guide bearing 21 having a bore 31 therein to guide the valve stem 18 in its movement when the trigger 27 is manipulated. The top of the valve stem 18 has secured thereto a button-head 22, the portion below the button-head 22 being counter-bored, in order to confine therein the resilient spring element 25 which is a compression type of spring, the top of the piston also having a keyway 23, which has a closed portion at the top thereof designated 24, so that when the button-head 22 is depressed below the lowermost portion of the portion 24, air will be allowed to filter into the water compartment, thus furnishing a venting means, so that the water, or liquid 45 that is dispensed therefrom, will be replaced by a quantity of air sufficient to maintain the physical equilibrium within the confines of the cavity 19.

To manipulate the valve 17, the trigger 27 is mounted pivotably at 28 on the two ears formed at the top portion of the piston casting, the said trigger being provided with a handle 29 which is the manipulating portion thereof, and an actuating portion 30, preferably of a hemispherical shape at its end, so as to equalize the frictional action over the top surface of the button-head 22, and to facilitate the translation of motion when the valve is manipulated; the valve being manipulated upwardly toward the dotted lines causing a depression of the valve 17 admitting some of the liquid into the compartment 12, release of the handle 29 causing the resilient spring 25 instantly to bring it back to normal position indicated by the full lines in Fig. 1.

To replenish the compartment 19 with liquid 45, a screw plug or filler means is provided and designated 32. By removal of the same liquid may be funnelled into the cavity 19, then the plug 32 caused to seal the same properly. The jack is provided with a cradle portion 43 at its top supported on suitable reinforcement 41 which, incidentally, provides the recessed opening 42 to mount the trigger mechanism therein. The cradle portion 43 may also be encased in rubber, or other non-marring resilient material, so that the bumper 44 of an automobile may be cradled therein when it is desired to jack up, or raise, or elevate an automobile, or similar load.

Another bumper support is also indicated and designated 37 which consists of a hook portion having a series of teeth 39 which are accurately formed, the said hook 37 being part of a ring structure 46, smoothly and rotatively operable about the outside of the piston body 20 at the upper portion thereof, and also the outside of the body 9 which is preferably finished so as to permit sliding of the ring-like structure 46, for effectuating a preliminary adjustment, thus minimizing the expansion requirement to be provided

by the chemical reaction taking place within the confines of the chamber 12.

This hook-like structure 37 is suitably encased in a rubber casing 38 to prevent marring the bumper structure 40, and it serves to cradle the bumper structure for elevation or lowering purposes, as the case may necessitate.

To the outer body portion 20 of the piston, I secure by welding or other suitable means, as indicated at 35, a rack 33 having teeth 34, which will cooperate and enter into meshing engagement with the teeth 39 in order to effectuate a fixed level position, as a preliminary setting preparatory to raising the bumper 40. The setting of this arrangement is made as follows: The jack is brought up to the car, and if desired, the hook 37 is grasped, and looking at Fig. 6, is rotated in the direction of the arrows 65, so as to bring the teeth 39 out of mesh with the teeth 34. Then the teeth 34 are brought into the confines of the clearance opening 61, thus permitting the ring 46 to be moved, vertically, up and down to whatever height is desired; then to maintain the ring at the proper height, or lowered position, the ring is swung in the direction of the arrows 65 from the dotted position back to the full position, causing the proper teeth 39 to enmesh with the teeth 34 in the elevation desired, thus raising or lowering of the hook-like support 37 may be effectuated.

The lower portion of the jack body 10 is provided with a threaded opening 60 to which I secure, the headed bushing 65 having a reduced shoulder portion secured attached by virtue of the threaded portion 66. The headed portion of the bushing 65 serves the purpose of confining rotatably the closure 47, or cap 47, which is in turn provided with a threaded portion secured to a threaded washer 67, rotatably operative about the body of the bushing 65, the head thereof confining the cap 47 from behind removed. The top surface of the cap 47 is provided with an opening 63 which is an elongated slot, and the body of the bushing is provided with a mating opening 52 therethrough, so that when the two are rotated to register in alignment as indicated in Fig. 1, a cartridge or pill 46 may be passed therethrough into the cavity 12.

The said opening may also be utilized for preliminarily moving the piston 14 upwardly when making a preliminary adjustment of the jack to meet the normal position of a bumper, when the car is resting on its wheels, the passageways 52 and 53 being in alignment permit air to come into the chamber 12, below the piston 14, so that when the same are closed or offset, as indicated in Fig. 4, the air confined therein will not escape and the chemical reaction to take place will generate additional gases to begin elevating the car, or the load.

The cap 47 is limited in rotation by virtue of having an undercut portion 49, and a screw 48 is secured, its head confining the rotational movement of the cap 47, which moves within an ambit as indicated approximately by the arrows 66. The central portion of the bushing 65 and the cap 47 have attached thereto a standard pneumatic valve 50, so that when a valve hose, or air pressure hose 51 is connected thereto, the said valve is automatically opened, and will permit the pressure confined within the compartment 12 to be passed out therethrough. Thus, if the car is to be lowered subsequently to its having been elevated, an air pressure hose 51 may be connected to the valve 50, and thus the gas confined therein

will come out rather slowly, and make for a very gentle lowering of the load, or automobile.

My invention may also be utilized as a pump aside from its ideal advantages as an automobile, or load elevating device, through the same operation, that is, by feeding, or passing a cartridge, or pill 46 into the confines of the chamber 12. After the piston will have reached its maximum travel wherein the lip 13 is in abutment with the shoulder on the piston, then a continual expansion of the gases will be forced out through the air hose 51, and inflate the tire 67 through its valve 68, or, in other words, act as an inflation pump by the use of the hose 69. When the jack is in its collapsed position, the shoulder 62 will rest against the shoulder 63. The jack piston can be easily manipulated by causing the alignment of the valve opening admitting air into chamber 12.

I believe, I have herein disclosed, and described, rather succinctly, the structure, the application, and use of my invention, and inasmuch as the same are susceptible of modification, improvements, and alterations, I hereby reserve the right to all such modifications, alterations, and improvements coming within the scope and spirit of my invention, as well as any of those that are impliably suggested or embraced in the accompanying drawings, and also all those that fall within the purview of the foregoing description; my invention to be limited only by the subjoined claims.

Having thus described and revealed my invention, what I claim as novel and desire to secure by Letters Patent is:

1. A combination inflation pump and load lifting jack comprising, a jack body, a hollow liquid retaining piston telescopically fitted to operate in the said body and having a head portion extending beyond the top of said jack body, means secured to the said head portion for cradling an engageable part of a load, valve means in the bottom portion of the said piston, trigger means cooperatively associated with the said valve means and adapted to open the same, cartridge insertion closure means secured to the lowermost portion of the said jack body, and inflation and exhaust valve means secured to the said closure means.

2. A combination inflation pump and load lifting jack comprising, a jack body, a hollow liquid retaining piston telescopically fitted to operate in the said body and having a head portion extending beyond the top of said jack body, adjustable means secured to the said head portion for cradling an engageable part of a load, valve means in the bottom portion of the said piston, trigger means cooperatively associated with the said valve means and adapted to open the same, cartridge insertion closure means secured to the lowermost portion of the said jack body, and inflation and exhaust valve means secured to the said closure means.

3. A combination inflation pump and load lifting jack comprising, a jack body, a hollow liquid retaining piston telescopically fitted to operate in the said body and having a head portion extending beyond the top of said jack body, toothed adjustable means secured to the said head portion for cradling an engageable part of a load, valve means in the bottom portion of the said piston, trigger means cooperatively associated with the said valve means and adapted to open the same, cartridge insertion closure means secured to the lowermost portion of the said jack body, and in-

flation and exhaust valve means secured to the said closure means.

4. A combination inflation pump and load lifting jack comprising, a jack body, a hollow liquid retaining piston telescopically fitted to operate in the said body and having a head portion extending beyond the top of said jack body, means secured to the said head portion for cradling an engageable part of a load, valve means in the bottom portion of the said piston, trigger means cooperatively associated with the said valve means and adapted to open the same, cartridge insertion closure means secured to the lowermost portion of the said jack body, inflation and exhaust valve means secured to the said closure means, and a base element articulately secured to the said jack body.

5. A combination inflation pump and load lifting jack comprising a jack body, a hollow liquid retaining piston telescopically fitted to operate in the said body and having a head portion extending beyond the top of said jack body, adjustable means secured to the said head portion for cradling an engageable part of a load, valve means in the bottom portion of the said piston, trigger means cooperatively associated with the said valve means and adapted to open the same, cartridge insertion closure means secured to the lowermost portion of the said jack body, inflation and exhaust valve means secured to the said closure means, and a base element articulately secured to the said jack body.

6. A combination inflation pump and load lifting jack comprising, a jack body, a hollow liquid retaining piston telescopically fitted to operate in the said body and having a head portion extending beyond the top of said jack body, toothed adjustable means secured to the said head portion for cradling an engageable part of a load, valve means in the bottom portion of the said piston, trigger means cooperatively associated with the said valve means and adapted to open the same, cartridge insertion closure means secured to the lowermost portion of the said jack body, inflation and exhaust valve means secured to the said closure means, and a base element articulately secured to the said jack body.

7. A combination inflation pump and load lifting jack comprising, a jack body, a hollow liquid retaining piston telescopically fitted to operate in the said body and having a head portion extending beyond the top of said jack body, means secured to the said head portion for cradling an engageable part of a load, valve means in the bottom portion of the said piston, trigger means cooperatively associated with the said valve means and adapted to open the same, cartridge insertion closure means secured to the lowermost portion of the said jack body, and inflation and exhaust valve means secured to the said closure means, the said closure means including, a headed bushing element secured to the said jack body, a cap element rotatably fitted on the head of said bushing element, a washer element secured to the said cap element rotatably fitted over the body and below the head of the said bushing element, a through passage-way in the said bushing element in eccentric relationship with the axis thereof, a mating opening in the said cap element adapted to register with the said passage-way, and means limiting the rotation of the said cap element.

8. A combination inflation pump and load lifting jack comprising, a jack body, a hollow liquid retaining piston telescopically fitted to operate

in the said body and having a head portion extending beyond the top of said jack body, adjustable means secured to the said head portion for cradling an engageable part of a load, valve means in the bottom portion of the said piston, trigger means cooperatively associated with the said valve means and adapted to open the same, cartridge insertion closure means secured to the lowermost portion of the said jack body, and inflation and exhaust valve means secured to the said closure means, the said closure means including, a headed bushing element secured to the said jack body, a cap element rotatably fitted on the head of said bushing element, a washer element secured to the said cap element rotatably fitted over the body and below the head of the said bushing element, a through passage-way in the said bushing element in eccentric relationship with the axis thereof, a mating opening in the said cap element adapted to register with the said passage-way, and means limiting the rotation of the said cap element.

9. A combination inflation pump and load lifting jack comprising, a jack body, a hollow liquid retaining piston telescopically fitted to operate in the said body and having a head portion extending beyond the top of said jack body, toothed adjustable means secured to the said head portion for cradling an engageable part of a load, valve means in the bottom portion of the said piston, trigger means cooperatively associated with the said valve means and adapted to open the same, cartridge insertion closure means secured to the lowermost portion of the said jack body, and inflation and exhaust valve means secured to the said closure means, the said closure means including, a headed bushing element secured to the said jack body, a cap element rotatably fitted on the head of said bushing element, a washer element secured to the said cap element rotatably fitted over the body and below the head of the said bushing element, a through passage-way in the said bushing element in eccentric relationship with the axis thereof, a mating opening in the said cap element adapted to register with the said passage-way, and means limiting the rotation of the said cap element.

10. A combination inflation pump and load lifting jack comprising, a jack body, a hollow liquid retaining piston telescopically fitted to operate in the said body and having a head portion extending beyond the top of said jack body, means secured to the said head portion for cradling an engageable part of a load, valve means in the bottom portion of the said piston, trigger means cooperatively associated with the said valve means and adapted to open the same, cartridge insertion closure means secured to the lowermost portion of the said jack body, the said closure means including, a headed bushing element secured to the said jack body, a cap element rotatably fitted on the head of said bushing element, a washer element secured to the said cap element rotatably fitted over the body and below the head of the said bushing element, a through passage-way in the said bushing element in eccentric relationship with the axis thereof, a mating opening in the said cap element adapted to register with the said passage-way, and means limiting the rotation of the said cap element.

in eccentric relationship with the axis thereof, a mating opening in the said cap element adapted to register with the said passage-way, and means limiting the rotation of the said cap element.

11. A combination inflation pump and load lifting jack comprising, a jack body, a hollow liquid retaining piston telescopically fitted to operate in the said body and having a head portion extending beyond the top of said jack body, adjustable means secured to the said head portion for cradling an engageable part of a load, valve means in the bottom portion of the said piston, trigger means cooperatively associated with the said valve means and adapted to open the same, cartridge insertion closure means secured to the lowermost portion of the said jack body, and inflation and exhaust valve means secured to the said closure means, and a base element articulately secured to the said jack body, the said closure means including, a headed bushing element secured to the said jack body, a cap element rotatably fitted on the head of said bushing element, a washer element secured to the said cap element rotatably fitted over the body and below the head of the said bushing element, a through passage-way in the said bushing element in eccentric relationship with the axis thereof, a mating opening in the said cap element adapted to register with the said passage-way, and means limiting the rotation of the said cap element.

12. A combination inflation pump and load lifting jack comprising, a jack body, a hollow liquid retaining piston telescopically fitted to operate in the said body and having a head portion extending beyond the top of said jack body, toothed adjustable means secured to the said head portion for cradling an engageable part of a load, valve means in the bottom portion of the said piston, trigger means cooperatively associated with the said valve means and adapted to open the same, cartridge insertion closure means secured to the lowermost portion of the said jack body, and inflation and exhaust valve means secured to the said closure means, and a base element articulately secured to the said jack body, the said closure means including, a headed bushing element secured to the said jack body, a cap element rotatably fitted on the head of said bushing element, a washer element secured to the said cap element rotatably fitted over the body and below the head of the said bushing element, a through passage-way in the said bushing element in eccentric relationship with the axis thereof, a mating opening in the said cap element adapted to register with the said passage-way, and means limiting the rotation of the said cap element.
